[57] CLAIM

The ornamental design for a humidifier dispersion tube, substantially as shown and described.

DESCRIPTION

FIG. 1 is a top plan view of a humidifier dispersion tube embodying my new design;

FIG. 2 is a front elevational view thereof;

FIG. 3 is a rear elevational view thereof;

FIG. 4 is a left end elevational view thereof;

FIG. 5 is a right end elevational view thereof; and
FIG. 6 is a cross sectional view taken on line 6—6 of FIG. 2.
